UNITED STATES PATENT OFFICE

2,585,039

LOCAL AUTOMATIC FIRE EXTINGUISHING SYSTEM

George E. Cooke, Providence, R. I., assignor to
George G. Evans, De-Kalb, Ill.

Application February 11, 1949, Serial No. 75,867

6 Claims. (Cl. 169—9)

1

The purpose of the present invention is to provide a means effective to extinguish interior fires before they have gained any substantial headway, and of such a character that it can be produced at low cost and installed readily in any location within a building where protection against damage by fire is desired. One particular phase of this general object which I have had in mind is to afford fire protection in rooms, hallways, closets, etc. of dwelling houses and apartments. There is a wide field of need and utility for the protection of living quarters such as those above mentioned. While numerous proposals have been offered for means to make a visible or audible signal at some central station when a fire occurs in living quarters, and many types of extinguishers have been made for manual use by one who is aware that a fire has started, yet no provision has been made, so far as I am aware, for actually extinguishing a fire in localities of that nature, automatically, when no one is aware that a fire has started. The sprinkler systems devised for factories are not suitable for installation in dwellings.

Hence I have sought to provide an apparatus or system which can be installed easily and at moderate expense in one or any number of the enclosed spaces of dwellings, which will convey extinguishing liquid directly to any part of the room where a fire has started, as soon as the fire has generated enough heat to melt or soften a small quantity of readily fusible or combustible material and before the fire has gained dangerous headway, and which is inconspicuous when installed.

The gist of the invention resides in a combination of a container for fire extinguishing fluid, a tube connected and communicating with such container adapted to be attached to the walls of a room at any height above the floor, being of any length sufficient to extend around the entire circuit of the room or any desired part thereof, normally having no outlet and being of a character such that it may be melted or burned through by impact of heat of moderate intensity, and electrical control means adapted to be put in action by the heat of a fire for opening a flow connection between the container of fluid and the tube. One illustrative embodiment of this combination is described in the following specification and illustrated in the accompanying drawings, in which,

Fig. 1 is a diagrammatic view of the combined system;

Fig. 2 is a sectional view of a portion of the 55 mounted between the necks of these cartridges.

2

tube element of the combination with a part of the electrical equipment of the combination inside the tube;

Fig. 3 is a partially dismembered view of a fragment of the electrical element shown in Fig. 2;

Fig. 4 is a partial diagram showing a modification.

Like reference characters designate the same parts wherever they occur in all the figures.

In this illustration, *a* represents a tank containing a fire extinguishing liquid, which may be plain water, a foam solution, or some noninflammable liquid other than water, such as carbon tetrachloride or the like. *b* represents an elongated tube which is coupled with the outlet passage *c* of the tank *a* and is closed at its outer end. Such tube is of a material which can be quickly disintegrated by heat, such as antimony, an alloy of antimony, or other metal alloy having a low melting point, and is made with thin walls so that it will be quickly melted at any point exposed to the heat of an incipient fire; the tube may be of any length suited to the condition of its installation and of a diameter generally proportional to its length. That is, tubes for installation where a relatively great continuous length of tubing is required may be of larger diameter than substantially shorter tubes. However, any tube applied to the purpose of this invention should have a large enough bore to conduct the extinguishing fluid quickly after communication has been opened with the interior of the tank to any point where a hole has been opened through the side of the tube.

When installed, and as long as no fire has occurred in the room where it is installed, the tube contains no liquid and has no discharge opening. It is shut off from communication with the body of extinguishing liquid in the tank *a*.

Any one of many means in the nature of a valve capable of being opened to admit liquid to the tube when need arises to use the liquid may be provided. In this illustration I have shown a type of tank which is in production and is available on the market, in which a hermetically sealed glass bottle or ampule *d* is contained within the shell of the tank and is supported above the bottom of the shell by a vertical tubular adapter *e*. This adapter and an extension tube *f* contain two sealed capsules or cartridges *g* and *g'* containing carbon dioxide under heavy pressure located so that their necks project toward one another. A double pointed piercing pin *h* is

3

in a tubular slide *j* fitted within the tube *f*. A plunger *k* is movable endwise in a guide extension of the sleeve *f* beneath the bottom of the cartridge *g*.

These parts are so arranged that when the plunger *k* is moved upward, it lifts cartridge *g*', causes the double pointed pin to puncture the end seal of this cartridge, raises the pin so as to puncture the end seal of cartridge *g*, and raises cartridge *g* so as to break the bottle *d* and allow the liquid to flow to the outlet port *c* and tube *b*. The carbon dioxide released from the cartridges flows through the adapter *e* to the top of the tank and applies pressure to the released liquid.

For releasing the liquid and pressure gas, I have provided here an electrically controlled device, the action of which is initiated by heat. A weight *l* is suspended by a trip *m* at the upper end of a guide *n*, and a lever *o* is pivoted at *p* to the wall bracket, pedestal or other device which supports the tank *a*. One arm of the lever extends under the lower end of guide *n* and the other arm extends under the plunger *k*. By this arrangement, the weight *l*, when allowed to fall strikes lever *o* suddenly and with great force, causing plunger *k* to be raised with the effect of piercing the gas cartridges and breaking the bottle of extinguisher fluid as above described.

For releasing the trip *m* I have provided a solenoid *q*, the core of which is coupled with the trip *m* in a manner such as to disengage the trip from the weight when the solenoid is energized.

The solenoid winding is in open circuit connection with a source of electric current *r* and two conductors *s* and *t* which enter the tube *b* through an opening, which is sealed liquid tight around the conductors, and extend within the bore of the tube to its outer end. The conductors are insulated from each other in such a manner, and are otherwise so related that the application of heat causes the insulation between them to be destroyed so that they come together in electrical contact.

I have found it satisfactory to use as such conductors a two wire cable put out by The Protecto Wire Co. of Hanover, Massachusetts, under the trade name of "Protectowire." This cable consists of two steel wires coated with thermoplastic insulating material, twisted around one another and covered with a light braid. The thermoplastic insulation is softened by heat and, where this occurs, the spring pressure under which the steel conductors are confined, causes the conductors to force the insulation aside and to come into contact, thus completing the circuit between the current source *r* and the solenoid *q*. Any suitable material such as a wax can be used as the thermoplastic material, carnauba wax, montan wax, and beeswax being examples. The choice of material will depend upon the temperature at which it is desired that the material melt.

The cable as a whole with its braided covering is designated *u* in Figs. 2 and 3, and is shown in Fig. 2 as contained within a fragment of the tube *b*.

When installed, the tube *b* with the contained electrical conductors, is attached to the wall or walls of a room in any convenient and desirably inconspicuous location, as along a baseboard, beside a molding or cornice, or elsewhere. The tank may be installed in an inconspicuous corner of the same room, or in a different room or closet and the tube run through the intermediate

partition or floor. Any room, or every room of a house may be thus provided with its own unit system, or one such system may serve for two or more adjoining rooms. Necessarily the tube is exposed in a manner such that it will be quickly affected by the heat of any fire which may develop in the room where installed.

In case of fire, the point in the side of the tube which is most quickly and highly heated is fused or softened and the insulation of the contained conductors is softened at the same time so that contact is made between the conductors. Thereupon the electric actuator (solenoid *q*) is energized to cause flow of the extinguishing fluid into the tube *b* in the manner precedently described. The fluid is then discharged on the fire from the opening in the side of the tube caused by the fire.

A signal device is associated with this apparatus to give notice at any suitable or desirable location whenever a fire has occurred. In the present illustrative diagram such signal device *v*, which may be an electric light, a bell, a buzzer or any other suitable device is connected in circuit with the current source *r* and with a normally open circuit closer *w*. The latter is suitably arranged to be closed by the weight *l* when the latter is released in the manner described. One suitable arrangement is that here shown, where the circuit closer is a pivoted lever and is connected by a link *x* with the lever *o*; the arrangement being such that when the right hand arm of lever *o* is depressed by the weight, the circuit closing arm of switch *w* is raised to engage a contact *y* connected to one of the conductors of the signal circuit.

Instead of employing electrical means to govern the application of force to release the extinguishing fluid upon occurrence of a fire, the same result may be obtained by mechanical means. One form of such mechanical means is illustrated in Fig. 4, where the latch *m* which normally supports the weight *l* is connected with a spring *10* so arranged as to tend constantly to release the latch. This tendency is resisted and overcome by a cord *11* which may be made of a thermoplastic, or other readily fusible or combustible material. It is connected with the latch so as to hold it in its supporting engagement with the weight and is led over or around guides, one of which is indicated at *12* so as to extend across any selected parts of the room or space in which the tank of fire extinguishing liquid is installed. In other respects the apparatus may be identical with that shown in Fig. 1, the only difference being in the substitution of the spring *10* and cord *11* for the solenoid *q* and electrical circuit.

It will be understood that the principles of the invention are not limited to the specific details of apparatus here shown illustratively. The tank element of the combination may be of any size and dimensions, for instance a large water tank installed at a great enough height to furnish a large pressure head. Various alternative forms of occlusion and release means may be provided for normally preventing access of extinguishing fluid to the tube and permitting such access at need, and various actuating contrivances may be applied for controlling such occlusion and release means, all within the scope of the present invention.

What I claim is:

1. A fire extinguishing apparatus comprising a tank, a thin walled tube made of material having a low melting point in flow-receiving connection

at one end with said tube and being closed against discharge at all other points, means in the tank normally preventing flow of fluid contained therein to said tube, means for opening the flow-preventing closure of said tank, and means extending along the said tube and responsive to a predetermined temperature at any point thereof to cause said opening means to operate.

2. A fire extinguishing system comprising a tank, a thin walled tube made of material having a low melting point in flow-receiving connection at one end with said tank and being closed against discharge at all other points, means in the tank normally preventing flow of fluid contained therein to said tube, a suspended weight, a lever pivoted a substantial distance below the level at which said weight is suspended, having an arm extending across the path in which the weight is adapted to travel when permitted to fall, force-transmitting means between the lever and container operable when the lever is displaced by impact of said weight to open a passage for fluid from the tank to the tube and heat controlled means for releasing the weight from its suspended condition.

3. A fire extinguishing system comprising a tank, a thin walled tube made of material having a low melting point in flow-receiving connection at one end with said tank and being closed against discharge at all other points, means in the tank normally preventing flow of fluid contained therein to said tube, a normally inactive electrical device disposed in relation to said flow-preventing means such as to disable said flow-preventing means when energized, and electrical conductors in open circuit connection with said electrical device and a source of current, extending in parallel throughout the length of said tube, being electrically insulated from each other and arranged to come into mutual contact when affected by heat sufficient to soften the wall of the tube.

4. A fire extinguishing apparatus comprising a tank, a tube connected at one end with an outlet port in the tank and being otherwise closed against outflow at all points, said tube having thin walls and being made of readily fusible

metal, a closed container of fire extinguishing liquid in the tank, means for opening said container so as to release the liquid comprising a suspended weight, a lever pivoted a substantial distance below the level at which said weight is suspended, having an arm extending across the path in which the weight is adapted to travel when permitted to fall, force-transmitting means between the lever and container operable when the lever is displaced by impact of said weight to open a passage for fluid from the tank to the tube, and a normally inactive electromagnetic device connected to release the weight when energized, and two electrical conductors in open circuit connection with said electro-magnetic device and a source of current extending throughout the length of the tube with thermoplastic insulation which is adapted to be softened by heat, said conductors being under spring pressure tending to bring them into physical contact.

5. A fire extinguishing apparatus as set forth in claim 2, in which a latch is provided to support the weight in suspended position and the heat controlled means are organized to release said latch when affected by sufficiently high temperature.

6. A fire extinguishing apparatus according to claim 2, in which a latch is provided to hold the weight in suspended position, a spring is connected with the latch under tension tending to disengage it from the weight, and the heat controlled means is a cord so connected to the latch as to prevent displacement thereof by said spring and being so positioned, and of such a character, that it is rendered inoperative for that purpose when subjected to heat of sufficient intensity.
